UNITED STATES PATENT OFFICE.

HENRY A. FRAMBURG, OF CHICAGO, ILLINOIS, ASSIGNOR TO H. A. FRAMBURG & CO.,
OF CHICAGO, ILLINOIS, A CORPORATION OF ILLINOIS.

LIGHTING FIXTURE.

Application filed February 1, 1924. Serial No. 639,882.

This invention relates to lighting fixtures.

Devices of this sort are usually an important factor in dressing up the room and their different arrangements in commercial and home lighting schemes make various ornamental and decorative structures as well as various types and degrees of ornamentation, desirable. Strength, symmetry and a pleasing appearance is required and simplicity in construction and assembly, minimization of the number of parts and the provision of a device that may be produced and ornamented simply and at a minimum cost is desirable. The matter of mounting or supporting the electric lamp or a plurality of electric lamps on such devices and the manner of concealing the conductors leading to the lamp or lamps so that the ornamental or decorative aspect of the fixture will not be impaired have also been important items to be considered. If the ornamentation is formed separately, additional steps are required and attachment to the fixture is involved. Formation of the ornamentation as an integral part of the fixture has been difficult especially on the thin walled lamp supporting arms where such arms are employed.

The primary object of my invention is to overcome the foregoing difficulties and provide a fixture which will meet the above requirements.

To these ends I find that by forming the lamp supporting arms of the fixture of thin walled tubular stock, preferably but not necessarily, square cross section I am able to produce an exceedingly pleasing aesthetic effect simply by shaping the arm lengthwise as desired, slotting it terminally and spreading or rolling the sides of the arm along the slot back to form an ornamentation. Where the lamp or lamps are supported on the arm the rolling back of the sides along the slot adapts the arm for the reception of a lamp nipple or support which can be simply and effectively brazed or otherwise secured in the open end of the tube between the rolled back sides, said rolled back sides masking and ornamenting the mounting of the lamp support and serving to brace it in its mounted position. The slotting and rolling back of the sides of the tubular arm along the slot

also adapts the end of the tube for the reception and mounting of a further ornamentation where that is desirable, serving to brace and hold the additional ornamentation properly positioned and by the use of either of these features alone or by the combination of the two, the ornamental mounting feature at one end of the arm and the lamp mounting feature at the other end a simple, pleasing and inexpensive fixture is provided.

The rolled back or spread ends are preferably flattened gradually from the square or polygonal formation at their bases toward their ends, the corners of the tube merging gradually into creases toward their outer ends which gives a pleasing appearance and a structure of great strength. Tubular stock of substantially square formation lends itself admirably to this formation. There is no buckling or drawing of the walls of the tube in rolling or spreading the ends.

In addition to improving the manner of ornamentation and the manner of supporting the lamp mounting or additional ornamentation, another feature is to improve the appearance of the entire fixture and to simplify and decrease the cost of the entire structure. This includes an improved manner of simply and symmetrically joining the arms together where a plurality of arms are employed, a simple and improved manner of attaching or mounting the arms upon the supporting bracket and an improved provision for masking the leading of the conductors into the arms.

The invention is illustrated in the accompanying drawings in which:

Fig. 1 is a front elevational view of a fixture embodying the invention;

Fig. 2 is a top plan view of the same;

Fig. 3 is a fragmentary vertical section on line 3—3 of Fig. 1;

Fig. 4 is a detail horizontal section on line 4—4 of Fig. 3;

Fig. 5 is a fragmentary section on line 5—5 of Fig. 2 through the upper end of one of the fixture arms;

Figs. 6, 7, 8, 9 and 10 are transverse detail sections taken on lines 6—6, 7—7, 8—8, 9—9 and 10—10 of Fig. 5 at the base of the

slot and at spaced points outwardly to the outer flattened end of one of the spread or rolled back sides of the arm;

Fig. 11 is a detail section on line 11—11 of Fig. 5;

Fig. 12 is a vertical section on line 12—12 of Fig. 2;

Fig. 13 is a side elevational view of an alternative embodiment of the invention; 10 and

Fig. 14 is a vertical section on line 14—14 of Fig. 13.

Referring to the drawings the fixture shown in Figs. 1 to 12 inclusive comprises a 15 support 5 in the form of a cast or otherwise formed wall bracket of brass, copper or other suitable or preferred material ornamented circumferentially at 6 and provided with a flat mounting wall 7. The base or bracket of 20 a fixture of this type is attached to the wall or other vertical support as by means of suitable screws and masks the outlet through which the conductors 8 (Fig. 3) extend from the wall. While base or bracket 5 is shown 25 of circular formation, it may be of any desired configuration and it may be ornamented or trimmed as desired. The particular base shown has formed integral therewith, although it may be brazed or otherwise secured thereto, an upwardly projecting scrolled ornament 10 and a downwardly extending ornament 12.

Detachably secured to the outer surface of the mounting wall 7 of base or bracket 6, so 30 that they may be used interchangeably with different bases and different bases may be used interchangeably with them, are a pair of arms 14 and 15. These arms 14 and 15 each comprises a thin walled tube of non-circular preferably square cross section. These tubular arms may be of copper, brass or other suitable material. The upper end of each arm 14 and 15 is turned out at 16 and slotted longitudinally from the end at 17. Longitudinal slots 17 extend parallel to one pair of parallel opposite sides 18 of the tube and divide the other pair of sides 19 (Fig. 6) thereby dividing or bisecting the upper end of each tubular arm into two opposed generally channel shaped ends 20 each having a flat base side terminating at its opposite ends in inturned flanges at substantially right angles thereto. The ends 20 are then spread and rolled out in opposite directions, as by means of a die or other suitable tool and in rolling said ends 20 the inturned flanges thereof are flattened gradually as shown in Figs. 7, 8, 9 and 10 into substantially the plane of the base side at their free ends. An ornamental scroll is thereby formed at the upper end of each arm 14 and 15. These ornamentations are of pleasing appearance and because of being integral with the arm, the ornamentation is exceedingly strong and sturdy. Attachment of

separate ornamentation to the arm is thus avoided and formation of the ornamentation integral with the arm is facilitated. There is no attachment to become loosened and the cost of the material, structure and forming or manufacture of the fixture is decreased.

I find that tubular stock of substantially square formation such as that shown lends itself admirably to this construction. The metal in the flat base side 21 of each end (Figs. 1 and 11) is displaced uniformly with the result that there is no buckling or drawing of the metal in rolling or spreading. The inturned side flanges 23 are simply turned out gradually into the plane of the base side toward the ends of the arm without buckling or drawing of the metal of the tube along that part. The gradual flattening of the inturned flanges into the plane of the base side gradually merges the substantially right angle corner 22 into creases or lines 24 toward the end of the tube and this still further improves the appearance or aesthetic effect of the ornamentation produced.

In practice an additional ornament shown in the form of a crystal drop 25 may be hung by a hook and eye 26 from each lower rolled out end 20, said rolled out end in such instances forming in addition to an ornamentation, a mounting for the additional ornament.

The lower end of each arm 14 and 15 is turned out and up at 28 and each upturned end is slotted longitudinally from the end at 29. The two channel shaped sides 30 at this end of the tube are then spread or rolled back and their inturned flanges 31 flattened gradually into the plane of the base side 32 as described in connection with the opposite ends to form an ornamentation and in addition to receive the lamp mounting designated generally at 35.

Each lamp mounting is in the present instance similar so that a description of one will suffice for both. It comprises a nipple 36 having its lower end reduced at 37 for insertion into the open end of the tubular arm and said end is inserted and brazed, soldered or otherwise rigidly secured in the end of the tube. Nipple 36 projects vertically upwardly from the end of the tube between spread or rolled back sides 20 and has flared sides 38 terminating in an annular shoulder 39. The rolled back base sides of ends 20 hug the flared sides 38 of the nipple upwardly a short distance at least from the lower end of the nipple and the inturned flanges 31 cooperate with shoulder 39 at 40 and brace the nipple above its lower anchored end to hold it securely in place and maintain the symmetry of the fixture. Nipple 36 has a flat radial shoulder 42 and an upright threaded extension 46 extending centrally therefrom and an annular cup 43

dished upwardly and decorated about its upper edge and outer surface at 44 has an annular base flange 45 mounted over threaded extension 46 and clamped between shoulders 42 and the lower end of a second nipple 47 threaded upon extension 46.

Cup 43 has an internal annular flange 48 and nipple 47 is threaded at 50 to receive a standard "Edison" or any other suitable or preferred lamp socket or connector for mounting one or more electric lamps. Nipples 36 and 47 are provided with aligned openings 51 and 52 through which the conductors 8 which enter tubes 14 and 15 through openings 55 (Fig. 3) and are led through the interior of the tubes, are permitted to extend for connection to the lamp socket or connector. The cooperation between the lower end of cup 43 and nipple 36 is such as to complete the finished appearance above the spread or rolled back ends of the tube and the cup conceals the connection to the lamp socket from view below.

25 Adjacent openings 55 arms 14 and 15 are brazed, soldered or otherwise suitably secured to the oblique sides 56 (Fig. 4) of a mounting member or block 58 which joins the two tubes rigidly together. Screws 58' 30 may be employed in addition for securing the arms to the mounting piece 58. Mounting member 58 is detachably secured to the mounting wall of base or wall bracket 5 by screws 60 which thereby detachably secure 35 the arms to the base or bracket of the fixture.

To conceal the attachment of the arms to the base or bracket of the fixture a plate or disc 62 ornamented as with a flowered 40 design as shown and with its upper and lower leaves turned outwardly and its side leaves turned inwardly into cooperation with the mounting surface of base 5 is mounted over arms 14 and 15 in front of their attachment to the wall plate. Plate or disc 62 has a central opening 63 for registration with a threaded opening in block 58 and with a registering opening in the mounting wall of plate or base 5 and a threaded stem 50 64 having an ornamented head or button 65 brazed or otherwise secured thereon for cooperation with plate 62 extends loosely through opening 63 and is threaded into block 58 and base 5 to hold plate or disk 62 securely in place. The attachment of the arms to the bracket and the leading in of the conductors is thereby effectively concealed.

In the modification shown in Figs. 13 and 60 14 the tubular arm 70 is again of square cross section with one end slotted at 72 and rolled back and gradually flattened at 73 to receive the lamp mounting 74 and to form an ornamentation adjacent the lamp mounting, the rolled back ends again cooperating

with mounting 74 at 75 to brace and hold it securely in place. The opposite end of the tube 70 is slotted longitudinally from its end at 76 and the side portions 78 are rolled back and gradually flattened to form an ornamentation and to receive an additional ornament 80. Ornament 80 is shown in the form of a relatively long curved leafed tendril and the inner end of said ornament is inserted and brazed, soldered or otherwise 75 suitably secured in the open end of the tube between rolled back sides 78, the rolling back of said sides forming an ornamentation and adapting the end of the tube for the reception of ornament 80 and bracing 80 and holding said ornament securely in place. The base sides 82 are rolled into the desired configuration and inturned flanges 83 are flattened gradually toward the end of the arm. 85

Thus the slotting and rolling back of the end of the tubes forms an ornamentation in each instance and in Fig. 1 it forms a mounting for the lamp support and in Fig. 2 a mounting for an additional ornament. 90 Also in Fig. 1 the upper rolled back end forms a mounting for an additional ornament where it is not desired to mount such ornament in the end of the tubular arm. These novel functions of the rolled back 95 ends are important along with the decorative or ornamental aspect produced.

The tubular arms shown in Figs. 13 and 14 may be mounted or supported in any desired manner. It may form part of a side bracket or wall fixture or of a hanging or any other type of fixture with which it is found adaptable. The invention is not limited to a particular type or class of lighting fixtures nor is it limited to embodiment in the lamp supporting arm of the fixture. Tubular stock may be formed as described for ornamenting the fixture whether the lamp or lamps are supported by said stock or otherwise and while thin walled tubular stock of substantially square cross section is desirable, stock of round elliptical or of hexagonal or other polygonal formation may be employed within the spirit and scope of the invention. 105 110 115

While I consider a square or rectangular cross section for the tube to be preferable, I do not wish to limit the invention to such tubing but wish to point out that it is easier to handle tubing which has its opposite sides parallel and also parallel to the plane of the initial slotting. Tubing having a cross section of any arrangement of flat sides will fulfill the requirement. A cross section of a regular polygon of an even number of sides such as a square, hexagon, octagon is suitable. 120 125

I do not wish to limit the invention to opposite scrolls because the effect may be obtained by one, two or more scrolls. As 130

above pointed out, the employment of a flat side as the basis of the scroll, and the merging of adjacent walls into such scrolls may be secured in a variety of ways. For example in a tube employing a hexagonal cross section may be slotted along three nonadjacent sides and thus three scrolls formed.

It is obvious that a square tube is admirably fitted because the slotting of opposite sides is easily accomplished at one operation.

10 A complete scroll or spiral of 360 degrees is not contemplated as necessary to the invention. Any suitable part of the same is sufficient.

15 I also wish to call attention to the fact that the slitting of the tube frees the walls so that as the freed portion is bent into a scroll or spiral the curvature of the cross section may be diminished and if desired as 20 in the case of a round tube carried past the zero value.

The ends do not need to remain square, they may be formed into ornamental shapes.

I claim:—

25 1. A lighting fixture comprising, a support and at least one hollow arm attached intermediate its ends, to the support; said arm being split at both ends and these split ends turned back into scrolls, those at one end at least being substantially symmetrical and formed to support a lamp mounting therebetween.

30 2. A lighting fixture comprising; a support and at least one hollow arm attached intermediate its ends to the support, said arm having a polygonal cross section preferably in the form of a square and split at both ends substantially on a line joining the middle of two opposite sides and these split ends turned back into scrolls which vary gradually in cross section, those at one end 35

at least, being formed to receive a lamp mounting.

3. A lighting fixture comprising; a support and at least one hollow arm attached 45 to said support, said arm being constructed of material which can be readily split and rolled and the arm at one end at least, being split and rolled back into scrolls so as to support a lamp mounting between the scrolls. 50

4. In a lighting fixture, a support, a tubular arm slotted terminally and having its sides adjacent the slots spread outwardly and flattened gradually, the said sides of the slots being adapted to receive a lamp mounting, a conductor entering the arm adjacent its attachment to the support, and means concealing the attachment of the arm to the support and the entry of the conductor into the arm. 55

60 5. In a lighting fixture, a wall bracket, a plurality of lamp supporting arms slotted terminally and having their sides formed into scrolls which vary gradually in cross section from a section of a portion of the tube to a section of a flat sheet, said scrolls being adapted to receive lamp mountings, the arms and bracket having apertures for the introduction of conductors into the arms for extension therethrough, a mounting member 65 attached to and rigidly joining the arms, means cooperable with the bracket and said mounting member for attaching the arms to the bracket, a plate concealing said attachment and the introduction of the conductors into the arms, and means cooperable with the mounting member in said plate for mounting the plate in place. 70

In witness whereof, I hereunto subscribe my name this 29th day of January, 1924.

HENRY A. FRAMBURG.
